CHOCOLATE CONFECTION

Amilcare Dogliotti, Neive, Cuneo, Italy

Filed Mar. 4, 1969, Ser. No. 16,017

Claims priority, application Italy Sept. 12, 1968

Term of patent 14 years

Int. Cl. D1—02

U.S. Cl. D1—12

FIG. 1 is a perspective view of a chocolate confection showing my new design;

FIG. 2 is an end elevational view;

FIG. 3 is a side elevational view; and

FIG. 4 is a top plan view thereof.

I claim:

The ornamental design for a chocolate confection, substantially as shown.
